(57) **CLAIM**

The ornamental design for a bottle-shaped portable music player speaker and amplifier assembly, as shown and described.

DESCRIPTION

FIG. 1 is an exploded perspective view of a bottle-shaped portable music player speaker and amplifier assembly showing my new design;

FIG. 2 is front elevational view thereof;

FIG. 3 is a right side elevational view thereof, the opposite side being a mirror image;

FIG. 4 is a rear elevational view thereof;

FIG. 5 is a top plan view thereof;

FIG. 6 is a bottom plan view thereof; and,

FIG. 7 is a reduced perspective view thereof.

The broken line showing on the drawing disclosure is for illustrative purposes only and forms no part of the claimed design.
